PRESSING MACHINE

Samuel Goldstein, New York, N. Y.

Application June 24, 1947, Serial No. 756,749

3 Claims. (Cl. 38—15)

1

This invention relates to pressing machines of the character used for pressing articles of wearing apparel or portions thereof, and has for its main object the provision of a machine of this character which will effectively perform the functions for which it is intended with a minimum of manual effort on the part of the operator.

In machines of this character, an example of which is shown in my Patent No. 2,197,613, dated April 16, 1940, means is provided for applying a vacuum or "suction" to the interior of the buck upon which the article to be pressed is supported, for the prompt removal of the moisture from the garment upon lifting movement of the pressing iron. In most machines of this character, including that disclosed in the above-mentioned patent, the valve controlling vacuum operation is operated by means supplementary to the foot treadle employed for lowering the pressing iron. The supplementary means for operating the valve requires certain manual adjustment, and the result is that a careless operator very often fails to operate the vacuum control so that inefficient and unsatisfactory operation of the machine is often had.

An important object therefore, of the present invention is to provide means for automatically controlling the vacuum valve so that said valve will be held closed when the pressing iron is lowered down upon the buck and said valve will be automatically opened when the treadle is caused to rise to elevate the pressing iron. The result of this arrangement is that a vacuum is automatically exerted through the buck at the proper time, namely, when the iron is moved away from the buck and at all other times the vacuum is shut off by the closure of its control valve, the closure thereof being controlled by the descent of the treadle.

Another object of the invention is to provide, in a structure as above described, means by which the vacuum control valve may be permitted to close while the treadle is raised to thereby render the vacuum-creating means inoperative during periods when the machine is not in use.

In the accompanying drawing forming a part hereof, in which an illustrative embodiment of the machine is disclosed, Fig. 1 is a vertical sectional view of the machine, showing particularly the parts thereof to which the present invention relates, and with the vacuum-control valve in open position; Fig. 2 is a sectional view taken on the line 2—2 of Fig. 1, looking in the direction of the arrows; Fig. 3 is a view similar to Fig. 1, but showing the treadle in lowered position and the vacuum-control valve in closed position, and Fig. 4 is a sectional view taken on the line 4—4 of Fig. 3, looking in the direction of the arrows.

The elements of the machine are either mounted in or supported by the frame which in-

2

cludes a horizontal top or table portion 1, sides 2, supporting feet 3 and a front bar 10, the entire frame or parts thereof being preferably but not necessarily castings. Mounted above the top of the table 1 on the bracket or other support 6, is the buck 4, which may be of any suitable shape to effectively accommodate the garment or portions of the garment or other article to be pressed. The buck 4 is of hollow construction and is formed with an upper chamber 5 and a lower steam chamber 7. The top of the buck is provided with a plurality of perforations 8 through which moisture may pass to enter the chamber 5. Leading into the lower chamber 7 is a pipe or tube 9 through which steam, emanating from a suitable source, enters the chamber 7 and heats the buck, the condensation passing out of the buck through a pipe or tube 11.

Mounted above the buck is a pressing iron 12 which is heated by steam, gas, electricity or other suitable source of heat, and is provided with an operating handle 13, the iron being universally pivoted at 14 in the end of a bar 15 slidably mounted in an arm 16. The arm 16 is pivoted 20 on a vertical pivot 17 in the end of a pivoted pressure-arm 18, said arm 18 being pivotally mounted at 19 in bosses provided in upstanding portions 20 on the frame of the machine.

The arm 18 has its lower end pivotally connected at 21 to one end of a short link 22 which has its opposite end pivoted at 23 to one end of a lever 24. Lever 24 is pivoted between its ends at 25a, to the lower end of a suspension link 26 having its upper end pivoted at 27 in bearing 28 formed on the underside of the top 1 of the frame. Near one of its ends, the lever 24 is pivotally connected at 25 to the upper end of a link 29 which has its lower end pivoted at 30 to a treadle 31. At its rear end, the treadle 31 is formed with a clevis 32 pivotally supported from the bosses 34 on the sides 2 of the frame near the base thereof. A spring 35 has one end extending through an eye 36 on the underside of the top 1 of the frame, and has its other end connected to the pin 37 secured in the end of the lever 24 near the pivot 25.

Through the mechanism thus far described, it will be apparent that when the foot plate 38, provided at the free end of the treadle 31, is depressed, link 29 will be drawn downwardly, said link exerting a downward pull on the pivot 25 in lever 24, the opposite end of the lever 24 rising to swing the lower portion of the arm 18 rearwardly on an upward arc to cause arm 16 to bring the pressing iron 12 downwardly toward the buck 4. Means for adjusting the pressure of the iron 12 against a garment resting on the buck, is provided, as will be described.

At 39 is shown an adjusting link which has one of its ends pivotally connected at 40 to the de-

pendent link 26 at a point between the pivots 25a and 27.

The opposite end of adjusting link 39 receives the threaded end 41 of an adjusting screw which is freely rotatably mounted in the front bar 10 of the machine and in a bracket member 47 secured to the front bar 10 and is provided with a handwheel 43 located at the front of the machine above the foot plate 38 of the treadle so that it is convenient for manipulation, whenever desired.

It will be obvious that by rotation of the hand wheel 43, the threaded end 41 moving through the end of the adjusting link 39 may move the adjusting link longitudinally either to or from the front of the machine. When the adjusting link 39 is moved toward the front of the machine by rotation of hand wheel 43, it will swing the link 26 on its pivot 27 in the same direction, this action tending to exert a similar pull on lever 24, which, through its connection with the lower end of arm 18 through link 22, will tend to swing said arm 18 on its pivot 19 in a counterclockwise direction, as viewed in Figs. 1 and 3, so that the pressing iron 12 will be elevated and adjusted in a direction away from the buck. Thus, when pressure is applied on the treadle 38 to lower the iron 12, a lighter pressure of the pressing iron 12 on the buck will take place.

When the adjusting wheel 43 is rotated in a direction opposite to that just described or in other words, away from the front of the machine, a reverse action occurs. That is to say, the pressing iron is brought closer to the upper face of the buck and greater pressure of the iron thereon will follow when the treadle 31 is depressed. Thus, by simple manipulation of the hand wheel 43, conveniently located at the front of the machine, adjustment of the pressure imposed by the pressing iron 12 upon the buck can be had. A spring 44 surrounds the adjusting screw 41 and exerts friction to hold the screw in any set position of adjustment.

When the foot plate 38 of the treadle is depressed, means is provided for holding the treadle in such depressed position, as shown in Fig. 1, for any desired period of time. Such means includes a gravity-operated latch member 45, pivoted at 46 at its upper end in supporting member 47, secured on the front bar 10 of the machine. Said latch member 45 is provided at its lower end 49 with the rod 48 arranged to have its lower end 49 engage one or the other of the notches 50 provided on the top of the treadle 31 to hold the treadle in its depressed position. When the treadle 31 is depressed as shown in Fig. 3 by foot pressure imposed on the foot plate 38, latch member 45 will swing by gravity toward the right, when viewed as in Fig. 3, and the lower end 49 will engage in one or the other of the notches 50 on the treadle 31, the notch engaged being determined by the thickness of the goods then being pressed. When the latch member 45 so engages one of the notches and is in position shown in Fig. 3, it will hold the treadle down or in its depressed position as long as desired by the operator.

For releasing the latch member, I provide a bellcrank lever 51 which is pivoted at 52 between the walls of the slot 53 formed in treadle 31 near the foot plate 38 thereon. The bellcrank lever 51 is formed with an upwardly extending weighted end carrying a roller 54 which rides against a downwardly-extending lug or plate 55 provided on the latch member 45. Bellcrank lever 51 has another arm 56 formed with an up-

turned end terminating in a button 57 movable through an opening 58 formed in the foot plate 38 of treadle 31. When foot plate 38 is depressed, the foot of the operator at the same time extends over and so depresses button 57 and this serves to swing the weighted end 54 toward the right as viewed in Fig. 1, to permit the latch member 45 to also swing toward the right by gravity and engage one of the notches 50.

When it is desired to permit the treadle 31 to rise and correspondingly move the pressing iron 12 away from the buck, the foot plate 38 of the treadle (but not button 57) is pressed downwardly near its free end for a slight distance, to permit the end 49 of the latch member to swing toward the left under pressure of the roller-carrying end 54 of the bell-crank lever 51, thus releasing the end 49 of the latch member from its engagement with one of the notches 50, and enabling the treadle 31 to be drawn upward under the pull of the spring 35.

It will thus be clear that by foot pressure imposed on the foot plate 38, at the same time depressing the button 57, the treadle 31 will be forced downward to its lowered position, shown in Fig. 3, which action causes the pressing iron 12 to descend upon the buck with pressure governed by the regulating screw 41. The latch member 45 automatically engaging one of the notches 50, will hold the treadle in its depressed position as long as desired until the free end of the treadle is depressed, permitting the latch member to swing free of its engagement with the notch 50 under the pressure of the weighted end 54 of lever 51.

The upper chamber 5 of the buck 4 is connected to a pipe 60 having its lower end connected to a valve chamber 61, in which valve 62 is mounted. A pipe or tube 63 connects the valve chamber with a suitable vacuum pump or other suction-creating means. Valve 62 is provided with a stem 64 which extends out of chamber 61 and within the chamber 61 the stem 64 is surrounded by spring 65 serving to normally hold valve 62 in closed position, thereby closing communication between chamber 5 and the vacuum pump.

The valve chamber 61 is provided with a bracket portion 66 in which a bellcrank lever 68 is pivoted at 67. Said bellcrank lever 68 includes a forked arm 69 which fits around the valve stem 64 and is operative against the nut 70 thereon to open the valve 62 against the pressure of the spring 65. The second arm 71 of the bellcrank lever 68 takes the laterally projecting end 72 of the arm of a bellcrank lever 73 pivoted on the pivot pin 46. The second arm of the bellcrank lever 73 is pivoted at 74 to one end of a two-part toggle link 75 which has its opposite end pivoted at 21 to the lower end of the arm 18. The result of this arrangement is that when the treadle 31 is elevated under the pull of the spring 35, and the lower end of the arm 18 swings forwardly or toward the right in Figs. 1 and 3, the link 75 imparts a push upon bellcrank 73 swinging it on its pivot 46 and causing its laterally-extending end 72 to swing downwardly. The downward swing of the end 72 of the bellcrank 73 causes downward pressure to be imparted on the arm 71 of the bellcrank lever 68 and the second arm thereof, indicated at 69, will then exert a pull on the valve stem 64 to draw the valve 62 to open position.

As long as the treadle is in its raised position, as shown in Fig. 3, the valve 62 will be held open,

unless the operator purposely desires the valve to be closed, such as when the machine is not being used or when for any reason he purposely does not desire suction to be exerted through the holes 8 in the buck. In such case, while the treadle is in its raised position, the operator depresses the button 57, and this action will cause a lifter rod 77 carried by the lever 51 to have its free end 78a raised and to contact the toggle link 75. It will be noted that the toggle link 75 has a pivot 78 between its ends, and when the lifter rod 77 is moved upwardly in the direction of the arrow in Fig. 1, it will engage the longer or rear portion of the link 75 and will break or buckle the link 75 at its pivotal point 78, thus shortening the effective length of the link 75 and permitting the bell-crank lever 73 to swing clockwise, as viewed in Fig. 1, and allowing the bell-crank lever 68 to swing counter-clockwise and the valve 62 to close under pressure of its spring 65 and to remain closed until the treadle is depressed and then permitted to rise.

The construction described is such that each time that the treadle 31 is depressed by foot pressure imposed upon the foot plate 38, the parts will be placed in the positions shown in Fig. 3, wherein it will be noted that the valve 62 will, at that time, be in its closed position since the pressing iron 12 is then engaged in the pressing operation and it is not desirable to then be exerting suction through the holes 8 in the buck. When the treadle is permitted to be raised, which action will cause the pressing iron 12 to be elevated and will cause the lower end of the arm 18 to swing toward the right, the link 75 acts as a push rod to swing bell-crank 73 to the position shown in Fig. 3, the laterally extending end 72 of the bell-crank 73 depressing the arm 71 of the bell-crank 68, causing the second arm 69 thereof to exert a thrust on the valve stem 64 to bring the valve to open position. As long as the treadle remains in raised position, the valve 62 will remain open as described, unless the operator desires the valve to be closed, such as during periods of non-use of the machine. In such event, a light touch of the foot upon the button 57 will cause lifter rod 77 to be elevated and it will break or buckle the link 75 on its pivot 78, thus permitting bell-crank levers 73 and 68 to swing in opposite directions under the thrust of the valve spring 65 and the valve to close.

The operation of the device is such that the suction-creating means is automatic and each time that the pressing is taking place, while the treadle is in its depressed position, the suction-control valve 62 will be in its closed position. When the pressing operation is completed and the treadle is raised the valve 62 will be opened and will remain open while the treadle is in raised position, unless the operator desires to allow it to close, when as previously pointed out, a pressure exerted on the button 57 will cause that result.

The treadle 31 is provided with a bumper 80 which contacts with the lower end of the link 26, said bumper being provided with a soft terminal portion 81 to contact with the end of link 26 as the treadle 31 rises.

While I have herein described one embodiment of the invention, it is obvious that the same is not to be restricted thereto, but is broad enough

to cover all structures coming within the scope of the annexed claims.

What I claim is:

1. In a pressing machine, a buck, a pressing iron and means for moving it to and from the buck, said means including a treadle, the iron being carried by a pivotal arm which is pivotally connected to the treadle, suction-creating means connected to the buck and including a control valve, spring means for normally holding the valve closed, a pivoted member for opening the valve, a second pivoted member operative thereon to cause the first pivoted member to open the valve, a link connecting the arm and second pivoted member and operative to move said pivoted member to a position to cause opening of the valve only when the treadle is in a raised position, a pedal carried by the treadle and operative upon the link when the treadle is in a raised position to shorten the effective length of the link and allow the pivoted members to swing to positions to allow closing of the valve by its spring means.
2. In a pressing machine, a buck, a pressing iron mounted above the buck, means for supporting the iron and moving it to and from the buck, means coupled to the buck for exerting a vacuum within the buck, said vacuum-exerting means including a control valve, a treadle for causing the iron to be moved to and from the buck, linkage extending from said treadle to the control valve to open said valve when the treadle is raised, a spring for closing the valve while the treadle is depressed to bring the iron against the buck, the treadle being provided with an independently movable pivoted foot-controlled pedal adapted to be depressed to optionally render the linkage ineffective to open the valve when the treadle is in its raised position.
3. In a pressing machine, a buck, a pressing iron mounted above the buck, a pivoted arm for supporting the iron and moving it to or from the buck, a treadle pivotally connected to the arm and adapted to be depressed to bring the iron toward the buck, means coupled to the buck for exerting a vacuum within the same, said vacuum-exerting means including a control valve, valve-opening means coupled to the treadle, a spring for maintaining the valve in closed position while the treadle is in a depressed position, the valve-opening means causing opening of the valve against the force of the spring while the treadle is in a raised position, and a supplemental valve control including a foot-operated pedal pivoted on the treadle, and means connected to said pedal by which the valve-opening means will be rendered ineffective to hold the valve open and will permit the valve to close under the impulse of said spring when the pedal is depressed while the treadle is in a raised position.

SAMUEL GOLDSTEIN.
